ANTENNA

Wilhelm Moser and Wilhelm Peters, Berlin, Germany, assignors to Telefunken Gesellschaft für Drahtlose Telegraphie m. b. H., Berlin, Germany, a corporation of Germany

Application December 15, 1938, Serial No. 245,859
In Germany December 15, 1937

4 Claims. (Cl. 250—11.5)

It is known in the art to combine linear antennae, more particularly dipole antennae, in such a way that directional effects are produced. However, assemblies of this kind known in the art are always so designed that dipoles preferably of like length are fed with standing waves, such dipoles being mounted in a plane and being fed from energy feeder lines in such a way that the desired directional action results. Such planes containing dipoles, however, are operable, in any given instance, only with a definite wavelength since dipoles will work only at their own natural period of oscillation or a closely adjacent oscillation. It will be remembered that such dipole combinations or arrays have a reactance which is markedly dependent upon the wavelengths. In other words, they are not readily useful for operation on, say, very broad modulation bands of the kind employed, for instance, in television work.

The invention is concerned with antenna systems working with progressing or propagating waves (Beverage antennae). The constituents or elements of these, as known in the prior art, may consist of rectilinear or curved wires, optionally of combinations of these. The essential feature of the invention is that the end of each constituent or elementary antenna of the aerial system turned away from the feeding point delivers energy by way of suitably designed coupling means to the next antenna, the termination of each individual antenna being matched to its surge impedance.

In what follows a number of exemplified embodiments of the idea shall be explained more fully by reference to the accompanying drawings in which Figure 1 illustrates an embodiment of the invention, Figure 2 is a modification thereof and Figures 3, 4 and 5 are further applications of the invention to other forms of antennae.

Referring to Figure 1, the wires a_1, a_2, a_3, a_4 are a plurality of linear wires placed and directed parallel to one another. If desired, they may be disposed in one and the same plane. The length of the elementary wires and their angular directions in reference to the direction of the line connecting the base points b_1, b_2, b_3, b_4 , are, for example, so chosen that a main lobe of the characteristic arising with propagating waves will fall in this direction. The transmitter is connected at point b_1 , while at the opposite ends c_1, c_2, c_3, c_4 , respectively, coupling means d_1, d_2, d_3, d_4 , etc., are provided by which the energy reaching c_1 is transmitted in the absence of radiation and in suitable phase to point b_2, b_3, b_4 , respectively.

Figure 2 shows an exemplified embodiment of the invention in which the wires a_1, a_2, a_3, a_4 are connected at points c_1, c_2, c_3, c_4 , etc., the characteristic impedance of c_1, c_2, c_3, c_4 , etc., being made equal to the characteristic impedance of the line a_1, a_2, a_3, a_4 , etc. The lengths of the lines e_1, e_2, e_3, e_4 , etc., are so chosen that the lengths $a_1+e_1, a_2+e_2, a_3+e_3$, etc., result in transit times of the waves so that the radiation energy will be reinforced in the direction, for instance, $b_1, b_2, \dots$. For instance, if the distance b_1, b_2, b_3, b_4 , etc., is equal to $\lambda/4$, then a_1+e_1 must be made equal to an odd multiple of the quarter-wave. In order to obtain the correct phase in this kind of energy transmission from point b_1 to b_2 may also be insured as fundamentally known in the art, and, according to the invention, by inserting phase shifting means. Also, according to the invention, the connecting line e_1, e_2, e_3, e_4 could consist of non-radiating lines of a form known in the prior art, with matching transformers being then inserted between c_1 and e_1 as well as between e_1 and a_1 , etc.

Another exemplified embodiment of the invention is shown in Figure 3 in which long wire antennae of rhombic form as known in the art $f_1, f_2, \dots$ are connected in series. Rhomb f_1 is coupled at the input end b_1 with the transmitter s . The output end c_1 is associated by way of a suitably designed energy feeder lead d_1 , say, a parallel-wire line to the input b_2 of rhomb f_2 ; from the end c_2 of the latter by way of energy feeder d_2 to the input b_3 of rhomb f_3 , etc. In this arrangement the distance between points b_1, b_2, b_3 , and the length or phase transit times of the energy transmitting means d_1, d_2, d_3 are so dimensioned in line with what is known in the art that the energy becomes a maximum in the direction b_1, b_2, b_3 .

Another exemplified embodiment of the invention is shown in Figure 4 where several circles $a_1, a_2, a_3, \dots$, are disposed parallel and co-axially spaced equal distances apart. Circle a_1 is fed from the transmitter s ; its end c_1 is united with the beginning b_2 of the second circle by way of the energy feeder d_1 . Similarly, the end c_2 of circle a_2 is connected through the energy feeder with the ring a_3 . In this embodiment, the phase transit times of the transmission or feeder means $d_1, d_2, \dots$, etc., is so chosen that it is a whole multiple of 2π . What then results are circular horizontal diagrams, and focusing in the vertical.

Another embodiment of the invention is to combine elementary antennae in such a way that rows fed separately or in parallel result. An ex-

emplified embodiment of this idea is shown in Figure 5. Two or more parallel rows of elementary radiators are provided, and of these each radiator has only propagating waves. 5 Group 1 comprises the radiators g_1 , g_2 and g_3 ; the second group contains g'_1 , g'_2 , g'_3 , etc. The geometric distance between the groups is preferably $\lambda/2$. Feeding with energy is effected as shown in Figure 5, by way of the beginnings b_1 10 and b'_1 etc., of the groups in parallel and in phase. The transmission of the energy from the individual radiator g_1 to radiator g_2 together with the transmission lead from the radiator g_1' to radiator g'_2 forms a non-radiating energy feeder line whose characteristic impedance, according 15 to the invention, is chosen equal to the characteristic impedance of the radiators g_1 and g'_1 . The feeding of radiators g_3 and g'_3 is effected in a similar manner, and so on. The end radiators g_3 , g'_3 , as known in the art, are terminated by means i , i' , designed to preclude reflection and thus the formation of standing waves.

We claim:

1. An antenna system comprising a plurality 25 of coaxially arranged horizontal loop antennae, means for connecting said loop antennae in a series relationship, means for energizing said system connected to one of said antennae, said connecting means including phase adjusting means

whereby the energy in said loops is in an in-phase relationship.

2. An antenna system comprising a plurality of coaxially arranged horizontal single turn loop antennae, means for connecting said loop antennae in a series relationship, means for energizing said system connected to one of said antennae, said connecting means including phase adjusting means whereby the energy in said loops is in an in-phase relationship. 5

3. An antenna system comprising a plurality of coaxially arranged horizontal loop antennae, means for connecting said loop antennae in a series relationship, means for energizing said system connected to one of said antennae, the connecting means between each of said antennae having a phase transit time such that the energy in said loops is in an in-phase relationship. 10

4. An antenna system comprising a plurality of coaxially arranged horizontal loop antennae, 20 means for connecting said loop antennae in a series relationship, means for energizing said system connected to the lowermost of said antennae, the connecting means between each of said antennae having a phase transit time such that the energy in said loops is in an in-phase relationship. 25
